UNITED STATES PATENT OFFICE.

FREDERICK J. HOYT, OF CHICAGO, ILLINOIS.

SASH-LOCK.

SPECIFICATION forming part of Letters Patent No. 730,266, dated June 9, 1903.

Application filed January 26, 1903. Serial No. 140,535. (No model.)

To all whom it may concern:

Be it known that I, FREDERICK J. HOYT, a citizen of the United States, residing in Chicago, in the county of Cook and State of Illinois, have invented certain new and useful Improvements in Sash-Locks, which are fully set forth in the following specification, reference being had to the accompanying drawings, forming a part hereof, and in which—

10 Figure 1 shows my said new sash-lock in longitudinal vertical section and edge view applied to the meeting-rails of a pair of sash-frames in locked position. Fig. 2 shows the top or moving member of my said device in top or plan view as seen on the outer face, the attached parts of the opposite face being shown in broken lines. Fig. 3 shows the bolt-keeper in side elevation. Fig. 4 shows the bolt-keeper in end elevation.

20 Like reference-letters denote like parts always.

The object of my invention is to produce a sash-lock which locks the locking member of my device to its position, is readily and easily 25 applied and locked and unlocked, and is cheap and durable.

To attain said desirable ends, I construct my said new sash-lock in substantially the following manner, namely: I make a low 30 broad flat oblong box *a*, with a bottom and four sides, wherein a hinge *c* is formed in what forms the lower end wall of said box, on which turns the top or lid *b* of said box. Said box is let into the upper sash until the face of its 35 lid is flush with the face of the sash and in such a position therein that when said lid is opened its face lies on the top of the lower sash, as shown in Fig. 1. The said lid is also shown in its closed position on the box in said 40 figure in broken outlines, together with its attachments. On the inner face of said lid is a stop *g* for the bolt *e*, which reciprocates on said inner face. Said inner face is the top face of said lid when it is down or locked, as 45 shown in full lines in Fig. 1, and said bolt *e* slides within a keeper *f*, held by screws *k* to said lid-face, and immediately beyond said keeper is a hole *d* through said lid, which has a beveled edge *d'*, and through said opening 50 passes a keeper *j*, whereof its outer face *j'* is beveled to correspond with the beveled edge *d'*, and said keeper is secured to the top of

the lower sash by screws *l*, and into said keeper *j* is shot the bolt *e* until its handle or stop *e'* strikes the outer edge of the keeper *f* 55 and its point passes beyond the lower or inner edge of the opening *d*, and in said latter condition of said lid and bolt the upper and lower sash are securely locked together and cannot be changed or unlocked by any instrument capable of being passed between the meeting-rails of a pair of sash. At the outer end of said lid *b* is a lug or catch *h*, around which the wood is cut away to form a cavity *i* to admit the finger for bringing said lid 60 down into its locking position. A set of screws *m* through the box-bottom fasten the box to the sash. The beveled face *d'* engages the beveled face *j'* to bring the sash-rails into close and firm contact by the time the lid *b* 65 lies flat on the top of the lower sash, and at the same time the leverage and position of said lid are such as will tend to drive both upper and lower sash-frames longitudinally to their home. The said box *a* forms a bar-holder, 70 on which the locking-bar *b* turns and within which the mechanism to the lid is attached. It is not, however, essential to have a metal box, because the required room may be dug out of the wood of the sash; but the hinge *c* 75 must be held to its place, as shown.

What I claim is—

1. The combination with a hinged bar, having a hole through it, and provided on its inner face with a reciprocable bolt, and keeper 85 and stops for said bolt, and a four-sided receptacle in the upper sash for said bolt, bolt-keeper, and stops, of a keeper to engage said bar, through said opening, and to receive said bolt, substantially as specified. 90

2. The combination with a hinged bar, having a hole through it, and provided on its inner face with a reciprocable bolt, and keeper and stops for said bolt, and a four-sided receptacle in the upper sash for said bolt, bolt-keeper, and stops, of a keeper provided with a beveled face, to engage said bar, through said opening, to receive said bolt, substantially 95 as specified.

FREDERICK J. HOYT.
